ROTARY PUMPS

Oliver Maisch, Chicago, Ill., assignor to Tuthill Pump Company, Chicago, Ill., a corporation of Illinois
 Original application Mar. 13, 1956, Ser. No. 571,251, now Patent No. 2,909,124, dated Oct. 20, 1959. Divided and this application Apr. 29, 1959, Ser. No. 809,802 1 Claim. (Cl. 103—126)

This application is a division of my copending application Serial No. 571,251 filed March 13, 1956, now Patent No. 2,909,124.

This invention relates to small motor driven pumps and has for its object to produce a simple and inexpensive pump which can be cleaned quickly and easily so as to be kept in a thoroughly sanitary condition; thus guarding against contamination of liquids handled thereby, and the invention relates particularly to check valve structures adapted for use in such pumps and which may be readily disassembled and reassembled for cleaning purposes.

Aside from using in the construction of a pump materials that are not harmful to liquids passing through the same, one of the most important factors is the ability to dismantle the same so completely that every surface that touches the liquids can readily be exposed. This may be made possible through so constructing the pump that it may be completely dismantled and again assembled.

One of the objects of the invention is therefore to create such a structure that dismantling and assembling may be done entirely by hand, without reliance on tools.

The various features of novelty whereby the invention is characterized will hereinafter be pointed out in the claim; but, for a full understanding of the invention and of its objects and advantages, reference may be had to the following detailed description, taken in connection with the accompanying drawings, wherein:

FIG. 1 is an end view of a preferred form of my improved pump mounted on a motor;

FIG. 2 is a side view of the pump and motor;

FIG. 3 is a section through the pump, on a larger scale, on line 3—3 of FIG. 1;

FIG. 4 is a section on line 4—4 in FIG. 3, showing only the pump, proper;

FIG. 5 is a section through the pump, on the same scale as FIG. 3, on line 5—5 of FIG. 1; and

FIG. 6 is a view similar to FIG. 4 with the gears and sealing ring omitted.

Referring to FIGS. 1—6 of the drawings, 1 and 2 are two stainless steel discs lying flat against each other and forming a pump housing. A third disc 3 serves a backing plate; disc 2 lying between discs 1 and 3. Disc 2 is shown as being thicker than the other two discs so that it may be deeply recessed in the face in contact with disc 1 to create the pump chamber 4 of which the latter disc forms the cover. This pump chamber is of the conventional gear pump type, comprising two overlapping sections 4^a and 4^b. Disc 1 contains two openings, 5 and 6, which are respectively, the inlet and outlet for the gear chamber.

In chamber 4 are two gears 7 and 8. Gear 7 is mounted for rotation about a little stub shaft 9 rising from the bottom of said chamber and extending almost to disc 1. Gear 8 surrounds a shaft 10 that extends into the pump housing through an opening 11 in disc 3 and an opening 12 in disc 2 in registration with the latter opening. Openings 11 and 12 are so designed that there is formed between disc 3 and the pump chamber a pocket 12^a partially closed at the ends by discs 2 and 3.

Shaft 10 is provided with a radial pin 14 that fits slidably in a groove 15 opening into the axial bore 16 in gear 8. Shaft 10 is pinned to motor shaft 17 so as to rotate therewith. Fitting in pocket 12^a is an elastic pack-

2

ing ring 18, preferably in the form of an endless annular trough; the open side of the trough facing the pump chamber. This packing ring forms an effective seal around shaft 10 and against disc 3 to close the only outlet through the rear or bottom of the pump chamber.

In the face of disc 2 that engages disc 1 is an annular groove 19 encircling the pump chamber. In this groove is an elastic packing ring 20 which forms a seal between these two discs.

In openings 5 and 6 are fixed corresponding ends of nipples 21 and 22, respectively. Tubes 23 may be attached to these nipples when the pump is in use. In the absence of such tubes, caps 24 may be snapped over the ends of the nipples to keep out foreign matter.

The outlet nipple 22 is a check valve. This consists of a ball 25 cooperating with a valve seat on the inner end of a short sleeve or bushing 26 frictionally held in the inner end of the nipple. The grip of the sleeve is increased by an elastic packing ring 27 fitted into an external circumferential groove in the sleeve. The ball is normally held against the seat by a spring 13.

The entire pump assembly is clamped together and to an adapter 30 mounted on the casing of a motor by two screws 32 having wing heads 33. Each screw is also provided with an integral collar 34 which bears against the outer face of disc 1 when the screws are tightened. The holes in the three discs through which the screws pass are simple bores so that, once the screws are freed from the adapter, the entire pump comes apart; only shaft 10 remaining attached to the motor. Since pin 35, which secures shaft 10 to the motor shaft, is removable shaft 10 may be detached from the motor shaft for cleaning or other purposes.

It will be noted that the pump is eccentrically mounted with respect to the motor shaft. To ensure that the discs can be assembled only in the proper angular positions relative to each other and the adapter, the latter is provided with a pair of short dowel pins 36 that project from the face thereof far enough to pass through holes 37 in disc 3 and into registering holes 38 in disc 2. Disc 3 can be applied in only one way, namely, with opening 11 registering with opening 12 in disc 2 and with shaft 10. The identifying words "Out" and "In," adjacent to the outlet nipple and the inlet nipple respectively, aid the assembler in applying disc 1, knowing that the outlet must be at the left or, more certainly, that the words must not be upside down. Pins 36 also serve accurately to align the pump with the motor shaft, making it unnecessary for the screws 32 to perform that duty.

After the pump is detached from the motor the two gears may be caused to drop out by simply turning disc 2 over to bring the gears on the under side, and sealing members 18 and 20 may easily be detached. Also, the inner end 26^a of bushing or sleeve 26 in outlet nipple 22 is preferably so shaped that this element may be lifted out with one's fingers to permit the ball valve and spring to spill from the nipple.

It will thus be seen that the pump may quickly be so completely separated into its individual elements that cleaning and sterilizing of the pump may be carried out easily and effectively; dismantling and reassembling requiring no tools. Also, because the adapter is in the form of a ring, ready access is had to shaft 10 for cleaning purposes after the pump is detached. Furthermore, because of the structural characteristics of the pump, sterilization may be achieved by simply causing it to pump sterilizing fluids for a short period.

The gear pump heretofore described meters liquids and is therefore well adapted to pump liquids in small quantities even a drop at a time.

While I have illustrated and described with particularity only a single form of my invention, I do not desire to

be limited to the exact details so shown and described; but intend to cover all forms and arrangements coming within the definitions of the invention constituting the appended claim.

I claim:

In a sanitary gear pump for pumping edible syrups and the like and having a main housing section with a pump chamber in one face thereof, meshing pump gears disposed removably in the chamber, a housing cover secured in a quick detachable relation on said main section across said pump chamber, and inlet and outlet nipples fixed at their inner ends in and opening through said cover into the pump chamber to provide inlet and outlet passages for the pump chamber, the improvement which comprises an elongated expansive coil spring removably disposed within said outlet nipple and having an outer end seated in said outlet nipple near the outer end of such nipple, a ball removably disposed within said outlet nipple and engaged by and urged inwardly of such nipple by said spring, a short thick-walled sleeve removably fitted into the inner end of said outlet nipple and having a valve seat on its outer end engaged by said ball, said sleeve having an external groove extending around the same, an elastic ring disposed in said groove and engaging the inside of the outlet nipple to hold the sleeve removably in position in the

nipple, and said sleeve having a second groove thereabout in an exposed location adjacent the inner end of the sleeve to provide an annular handle for engagement to remove the sleeve and release the ball and the spring for individual cleaning of the ball, the spring, the sleeve and the inner surfaces of the nipple.
